UNITED STATES PATENT OFFICE.

KATHARINA WEGNER AND ERNST REPKE, OF BERLIN, GERMANY.

APPARATUS FOR THE TREATMENT OF CURVATURE, &c.

SPECIFICATION forming part of Letters Patent No. 681,174, dated August 20, 1901.

Application filed August 30, 1899. Renewed May 17, 1901. Serial No. 60,765. (No model.)

To all whom it may concern:

Be it known that we, KATHARINA WEGNER and ERNST REPKE, engineer, subjects of the King of Prussia, German Emperor, residing 5 at 66 Potsdamerstrasse, Berlin, W., Germany, have invented new and useful Improvements in Stretching and Straightening Apparatus for the Treatment of Curvature and other Similar Deformities, of which the following 10 is a specification.

The object of this invention is a new, practical, and polygonal combined stretching and straightening apparatus for curing in a simple manner and by mechanical means hunch-backs, protuberant chests, and other deformities of the human body and limbs, such as narrow or pigeon breasts and weakness of the 15 muscles.

With these ends in view the invention consists in the novel combination, arrangement, and adaptation of parts, as will be more fully described in the following specification, and the essential elements of which are recited in the appended claim.

25 In the accompanying drawings, which illustrate our improved surgical appliance, Figure 1 is a perspective view, Fig. 2 a side view, and Fig. 3 a rear view, of the same.

This new stretching and straightening appliance consists, essentially, of an upright *a* and of an inclined plane *b*, adjustable on the latter and comprising a ladder *b'* and a board *b''*, laid on the same and capable of being adjusted at any suitable angle or inclination, 30 so as to allow of its position being selected according to the particular case under treatment. To these two main parts of the apparatus—*i. e.*, the upright *a* and the inclined plane *b*—are secured all the principal instruments and appliances used for orthopedic treatment, in such a manner as to enable them to be used under the most varied circumstances. By way of example, a bar or board *c* may be secured to the upright *a*, upon which 35 the patient would be laid in a suitable position and hold himself by means of a handle (not shown in the drawings) for the purpose of being straightened. The inclined plane *b* carries, by means of straps secured to one of the ladder-rungs, a holder *d*, provided with 40 a suspending device for the head to support the patient, otherwise held by an elastic breast-band *e* and resting during the treat- 45

ment on the board *b''*, so that he may be free to move his head in the suspending device 55 and his body in the elastic or rigid band for the purpose of exercising his muscles in this position by means of elastic or inelastic ropes or cords *f*, which, in order to increase the resistance, may have an exchangeable weight 60 suspended intermediate of the two ends.

Instead of the holder *d* being suspended by a strap to the inclined plane, the same may be fastened by means of elastic or inelastic ropes *g*, also provided with an exchangeable 65 weight suspended intermediate of the ends, thus allowing the exercise of the muscles to be carried on by overcoming an adjustable resistance. The patient may also be suspended to the inclined plane *b* by means of two shoulder-straps, loops, or rings *i*.

The board of the inclined plane is suspended to the same by means of hooks or the like, so that it can be removed and used as a massage-plank, as shown in dotted lines in 75 Fig. 2. Furthermore, the fixed or elastic band can be used for straightening or reducing purposes by arranging it differently on the apparatus.

This apparatus can be erected within a very 80 small space.

Having now particularly described and ascertained the nature of our said invention and in what manner the same is to be performed, we declare that what we claim is— 85

In an orthopedic appliance applicable also for muscular exercise the combination with a portable upright, of a ladder adapted to be attached to the upright at various angles, a board for supporting the body adapted to be hooked onto the rungs of the ladder at various heights, a head-strap and an elastic breast-band for suspending the body, exercisers for the various muscles, said exercisers in connection with a counterweight and handles for employing same, substantially as described and shown and for the purposes indicated.

In testimony whereof we have hereunto set our hands in presence of two subscribing witnesses.

KATHARINA WEGNER.
ERNST REPKE.
